UNITED STATES PATENT OFFICE.

JOSEPH GUEST, OF HOMESTEAD, PENNSYLVANIA, ASSIGNOR OF ONE-HALF
TO W. H. R. HILLIARD, OF PITTSBURG, PENNSYLVANIA.

ROLLING METAL.

SPECIFICATION forming part of Letters Patent No. 636,521, dated November 7, 1899.

Application filed June 22, 1899. Serial No. 721,447. (No model.)

To all whom it may concern:

Be it known that I, JOSEPH GUEST, a resident of Homestead, in the county of Allegheny and State of Pennsylvania, have invented 5 a new and useful Improvement in Rolling Metal; and I do hereby declare the following to be a full, clear, and exact description thereof.

My invention relates to the making of angle-bars and plates therefrom, its object being 10 to provide for the rapid reduction of the metal from large ingots or billets, so as to produce with few passes two angle-bars at one time, and in addition, if desired, to provide for the 15 formation of two flat plates or bars from each such angle, so providing for the rolling of this class of articles by few passes.

The invention consists, generally stated, in reducing a square billet first to star shape 20 and then shearing the star-bar into two angle-bars, this being preferably accomplished by forcing the opposite faces of the opposite flanges into line with each other and then shearing in line with such opposite faces of 25 these flanges through the other flanges of the bar and so forming two angle-bars.

It also consists in certain other improvements in the rolling of the bars and in the rolls for rolling the same.

To enable others skilled in the art to practice my invention, I will describe the same more fully, referring to the accompanying drawings, in which—

Figures 1 to 9 are perspective views showing 35 the different sections of the metal in course of reduction, and Fig. 10 is a face view of rolls suitable for forming the same.

Like letters and numerals indicate like parts in each of the figures.

In practicing the invention as shown in 40 the drawings the square ingot or billet *a* is rolled to substantially the form shown in Fig. 2, having its outwardly-extending flanges *b*, with partially-developed flanges *c*, midway 45 on each side thereof, and in the next pass the partially-developed flanges *c* are brought into flange shape, producing a star-bar, as shown in Fig. 3, having flanges at right angles to each other, as shown at *d d' d'' d'''*. By one 50 or more passes the flanges on opposite sides of the bar are drawn out of line with each

other, as shown in Fig. 5—that is, say the flange on one side is forced downwardly and the flange on the other side forced upwardly until the upper face *e* of one flange *d* is 55 brought into line with the lower face *f* of the flange *d*, the flanges *d* and *d'* remaining in line with each other. The next pass of the rolls is constructed so as to sever the star-shaped bar so formed along the line of the 60 faces *e f* of the flanges *d d'* and so form the two angle-bars, one being composed of the flange *d* and the flange *d'* and the other composed of the flange *d''* and the flange *d'''*. It thus requires five or less passes to reduce the 65 metal contained in the square ingot into two separate angle-bars, while in so rolling the same the metal contained within the bars in their different forms is so disposed as to balance each other and prevent the bar from 70 stretching unevenly and so being forced out of straight or proper line. In so reducing the bar it may be desired to employ an intermediate pass, such as shown in Fig. 4, before bringing the blank to the shape shown in 75 Fig. 5 and ready to be severed into two angle-bars. The angle-bars so produced can be used as angle-bars, being given one or more finishing passes, if necessary, or can be utilized in forming other shapes, such as by 80 spreading out the angle-bars, as shown in Fig. 7, and then forming flat plates or skelp therefrom, as shown in Fig. 8, or, if flat plates or bars of less width are desired, the angle-bars, such as shown in Fig. 6, can be sev- 85 ered close to the connecting-angle *k* and two bars *l m* produced therefrom, as shown in Fig. 9, in this way providing for the formation of four or more rectangular bars from the original billet by very few passes. 90

In Fig. 10 are shown rolls with an arrangement of passes suitable for practicing the method above described, the desired passes for such work being shown at 1, where the billet is rolled to the form shown in Fig. 2, 95 2 and 3, where the star-bar is produced, and 4, where the opposite flanges are drawn out of exact line with each other—that is, so that their opposite faces *e* and *f* will be drawn into line with each other, as shown in Fig. 5—5 100 showing the pass for severing the star-bar into two angle-bars. The passes 6 and 7 illustrate

the flattening of said bar to produce wide plate or skelp, while the pass 8 provides for the severing of the angle-bar into two narrow bars which can be finished, if desired, in the 5 pass 9.

The advantages of the invention should be apparent to those skilled in the art, as it provides for the rolling of two angle-bars at one time and overcomes the necessity of so great 10 reduction from the original billet, providing for the production of such angle-bars in five or less passes and providing for the production 15 of two flat bars from each angle by a single extra pass or for the opening out of the angle-bar into flat plate or skelp by one or more single passes. The cost of rolling is therefore very materially reduced.

What I claim as my invention, and desire 20 to secure by Letters Patent, is—

1. The method of rolling angle-bars, consisting in reducing a square billet to star shape and then shearing the star-bar into two angle-bars, substantially as set forth.

2. The method of rolling angle-bars, consisting 25 in reducing a square billet to star shape and forcing the opposite faces of two opposite flanges into line with each other, and then shearing along the line of said faces through the other flanges of the star-bar, so 30 forming two angle-bars, substantially as set forth.

3. The method of rolling flats, consisting 35 in reducing a square billet to star shape, and then shearing the star-bar into two angle-

bars, and then shearing the angle-bars so produced along the line of the angle and so forming two flat bars from each angle, substantially as set forth. 35

4. In the rolling of angle-bars, rolls having passes arranged to form a star-bar, and a pass 40 to shear the same at its meeting angles into two angle-bars, substantially as set forth.

5. In the rolling of angle-bars, rolls having preliminary passes arranged to form a star-bar, then a pass arranged to force the opposite 45 faces of two opposite flanges into line with each other and a succeeding pass arranged to shear through the bar in line with said faces, substantially as set forth.

6. In the rolling of angle-bars, rolls having 50 passes arranged to form a star-bar, and a pass arranged to shear through such star-bar at the meeting angles and form two angles, and a pass to shear through such angle-bar close to the angle thereof, substantially as set forth. 55

7. In the rolling of angle-bars, rolls having passes arranged to form a star-bar, and then a pass arranged to shear through such star-bar along the line at the meeting angles and form two angle-bars, and then passes arranged 60 to flatten out such angle-bar into flat plate, substantially as set forth.

In testimony whereof I, the said JOSEPH GUEST, have hereunto set my hand.

JOSEPH GUEST.
